CUTTER CHAIN AND CUTTER BAR

Robert K. Jeffrey, Columbus, Ohio, assignor to
The Jeffrey Manufacturing Company, a cor-
poration of Ohio

Application June 8, 1934, Serial No. 729,704
Renewed February 8, 1936

2 Claims. (Cl. 262—33)

The present invention relates to a cutter chain and cutter bar particularly adapted for use in a mining machine.

Objects of the invention are, to provide a cutter chain and a cutter bar for guiding the movement of the same which may be used in the cutting of a relatively narrow kerf, the cutter bar being so designed that the possibilities of binding in the kerf will be reduced; and to provide a cutter chain having links so designed with respect to each other as to resist any tendency of the links toward tilting or turning upon a transverse axis.

Other objects and advantages of the invention will be apparent from the following drawing, wherein like numerals refer to similar parts throughout the several views.

In the drawing:—

Figure 1 is a side elevation of a portion of the cutter chain;

Figure 2 is a transverse sectional view taken on the line 2—2 of Figure 1 and showing the cutter bar and the chain;

Figure 3 is a transverse sectional view on the line 3—3 of Figure 1;

Figure 4 is a side elevation of one of the bit carrying links of the cutter chain; and

Figure 5 is a side elevation of one of the connecting links used in the chain.

The numeral 10 designates the bit carrying links which are joined to form a cutter chain by means of connecting links 11. The bit carrying links 10 are of the bridged type, that is, as shown in Figure 3, they are substantially U-shaped in cross section, including side bars or plates 12 integral with a bridging portion 13. Each link 10 is provided with a projection or lug 14 extending outwardly from the bridging portion 13 and in which a cutter bit 15 may be clamped in any suitable manner. As is customary, the cutting bits of adjacent links 10 may project therefrom at various angles, as shown in Figure 2, in order to cut a kerf of the desired width.

A pair of connecting links 11 is provided to join adjacent bit carrying links 10, the links 11 of each such pair being within the side bars 12 of the bit carrying links and having their inner faces spaced apart to permit the chain to straddle the cutter bar 16. As best shown in Figure 2, the links 10 and 11 are pivotally connected by a rivet or the like 17, which rivet or other securing member passes through the aperture at each end of the plate or bar 12 of the bit carrying link 10 and extends into the aligned

aperture at the near end of the adjacent connecting link 11.

The cutter bar 16 upon which the chain moves is formed of outer plates 21 and an inner T-shaped plate 22, the T-shaped plate 22 extending past the outer ends of the plates 21 so that its head 23 is spaced from the plates 21. As shown in Figures 1 and 3, the bit carrying links 10 are provided on the inner walls of their side bars 12 with projections or lugs 24, the outer faces 25 of the projections 24 being straight or flat in a transverse direction, as shown in Figure 3, but the ends of these surfaces preferably being rounded as shown in Figures 1 and 4. The surfaces 25 are intended to be opposed to the inner surfaces of the head 23 of the cutter bar 16. The outer edges 26 of the connecting links 11 are also opposed to the inner surfaces of the head 23 on each side of the latter, thereby maintaining the chain in proper position with respect to the cutter bar 16. The plate 22 may be of hardened steel to make it wear resistant.

The inner surface of the lugs 24 may be cut away as shown in Figure 3 to permit fines to drop from the chain.

As best shown in Figure 2, the spacing between the inner surfaces of the head 23 of the cutter bar and the outer ends of the plates 21 forms a groove along each lateral surface of the cutter bar and the width of this groove is substantially the same as, or somewhat greater than, the width of the connecting links 11 and the distance from the inner edges of the side bars 12 of the links 10 to the outer surfaces 25 of the projections 24 on these latter links.

The provision of a cutter bar straddled by the cutter chain enables the entire structure to be of minimum thickness in a plane at right angles to the plane of the cutter bar, as shown in Figure 2, so that when a kerf is cut, only a relatively small quantity of coal will be mined as slack. Also, the substantial distance indicated at A in Figure 2 between a wall of the cutter bar and the adjacent wall of the kerf insures that, even with a narrow kerf, the movement of the cutter bar will not be cramped.

It will also be observed that because the cutter chain straddles the cutter bar instead of moving within the cutter bar, as in the usual construction, the "dead" area of the cutter bar will be reduced. That is to say, by having the chain straddle the bar, the "dead" or non-moving area of the bar is reduced and replaced by an increased exposed area of moving chain. A moving element such as the chain will not bind in the kerf and

5 by increasing the area of the moving element exposed in the kerf and at the same time decreasing the exposed area of the non-moving member, the cutter bar itself, the possibility of binding 5 of the cutter bar in the kerf is correspondingly reduced.

10 The inner surface 27 of the bridging portion 13 of the bit carrying links 10 may be arcuate, as shown, in order to permit these links to move 10 about the usual curved end of the cutter bar 16.

15 As is shown in Figures 1 and 5, lugs 28 are provided on the outer surfaces of the connecting links 11, preferably between their ends, the outer surfaces of these lugs being flush with the outer 15 edges 26 of the connecting links. Shoulders 29 are provided at the ends of the bit carrying links 10, and as shown in Figure 1, these shoulders are intended to contact with the outer surfaces of the lugs 28. By this arrangement, should one 20 bit carrying link 10 tend to tilt or turn upon a transverse axis, that is, rise at an angle to the cutter bar 16 by reason of engagement of its bit 15 with the coal, the shoulder 29 at the end of the bit which tends to move inwardly will contact 25 with the lug 28 carried by the adjacent connecting link. The connecting link will therefore resist the tilting of the bit carrying link. As is best shown in Figure 1, the ends 30 of the bit carrying links are closely adjacent each other and are 30 of substantial thickness. Therefore, when a connecting link tends to tilt, its tilting action will also be resisted by the adjacent bit carrying links as well as by the shoulders 28 on the connecting links.

35 By the above arrangement, a sharp tendency of one link to tilt will be transmitted through a number of adjacent links so that each link in the series affected will act to distribute the tendency to tilting and the length of chain involved in this action will remain substantially straight 40 or "stiff-backed".

It will be understood that the invention is not limited to the details of construction shown in the drawing and described in the specification and that the example of the use of the invention which has been given does not include all the 5 uses of which it is capable; also, that the phraseology employed in the specification is for the purpose of description and not of limitation.

I claim:—

1. In a kerf-cutter for mining machines, the 10 combination with a cutter bar having an outwardly extending rib less in thickness than the body of the cutter bar to afford shoulders on opposite sides of the cutter bar along the outer edges thereof and along the curved outer edges 15 thereof in parallelism with the outer edge of the rib, and a chain cutter comprising bit carrying links each comprising spaced straps with curved surfaces adapted to move along said shoulders including the outer curved ends thereof, said 20 straps being connected by a member having spaced straight surfaces connected by a curved surface, said straight surfaces being adapted to ride along the outer lateral edges of the rib and said curved surfaces between said straight surfaces being adapted to ride along the curved outer end of said rib.

2. In a kerf-cutter for mining machines, the 25 combination with a cutter bar having an outwardly extending rib of less thickness than the body of the cutter bar, the outer end of the cutter bar including said rib being curved, and a chain cutter comprising bit carrying links each U-shaped to straddle said rib and each having inner spaced straight surfaces connected by a curved 30 surface, the straight surfaces being adapted to ride along the lateral edge of the rib and the curved surface being adapted to ride along the outer curved end of the rib.

ROBERT K. JEFFREY.
